UNITED STATES PATENT OFFICE.

CLARENCE W. LUCAS, OF DECATUR, ILLINOIS, ASSIGNOR TO FARIES MANUFACTURING CO., OF DECATUR, ILLINOIS, A CORPORATION OF ILLINOIS.

ELECTRIC-LIGHT BRACKET.

1,107,811.

Specification of Letters Patent. Patented Aug. 18, 1914.

Application filed March 2, 1914. Serial No. 822,044.

To all whom it may concern:

Be it known that I, CLARENCE W. LUCAS, a citizen of the United States, residing at Decatur, in the county of Macon and State 5 of Illinois, have invented new and useful Improvements in Electric-Light Brackets, of which the following is a specification.

This invention relates to electric light fixtures, particularly to such as are designed 10 for temporary attachment to a bed, dresser, chair, or other article of furniture to concentrate the light, and which are capable of adjustment in a vertical and horizontal direction through an extensive range for the 15 purpose of positioning the light most advantageously for the person using it.

The object of the invention is to provide a bracket support of simple design that may be quickly and easily clamped on the post 20 or horizontal rail of a bedstead or other article of furniture, and with which bracket the curved arm of an electric light fixture is adapted to engage in such manner that it may be swung horizontally to adjust the 25 same laterally, or by moving the arm bodily within the bracket the vertical position of the light may be altered.

In the accompanying drawings, Figure 1 30 is a perspective view of the device in its preferred form applied to a vertical bed-post. Fig. 2 is a side view of the fixture. Fig. 3 is a view of the fixture applied to a horizontal bar. Fig. 4 is a perspective view 35 of the supporting bracket with the parts separated. Fig. 5 is a perspective view of a modified form of the bracket.

In the drawings, the supporting bracket 10 may be square, as shown, and made of two V-shaped frames 11 and 12, the ends of each 40 of which are bent outward in a plane to form feet 13; or the bracket may be annular and the frames 10 and 11 semi-circular. The shape of the bracket is immaterial and may be of any desired form. In the frame 45 11 are two slots 14 cut into the edge of said frame just back of the feet 13, and partway through the same. Similar slots 15 are cut into the member 12 on the opposite side so that said frames join when placed together 50 as in Figs. 1, 2 and 3, the slots 14 and 15 interengaging adjacent portions of the respective frames and lock the two together.

For the purpose of holding the bracket 55 upon a bed-post or other support A, a thumb-screw 16 is threaded through the an-

gular bend 17 of the frame 11 and when screwed tight bears firmly against the post and clamps the bracket 10 thereto.

Secured to the angle 18 of the frame 12 and projecting outwardly in line with the axis of the thumb-screw 16 is a head 19 of spherical form connected through a neck to the frame 12. Through the head 19 are formed two perforations 20 and 21 at right angles to each other, their axes lying in a plane perpendicular to the plane of the bracket 10.

An electric light fixture comprising a tubular arm 22 supporting at one end an electric light 23 and bent at its other end 24 in the segment of a circle is supported by the head 19, the curved portion 24 of the arm sliding freely through one or the other of the perforations 20, 21. The arm moves freely through the perforation and may be 70 swung horizontally to adjust the light laterally, or the curved portion 24 may slide through the head 19 when vertical adjustment of the light is required. The arm 22 will remain wherever placed, its own weight 75 clamping the curved portion thereof in the perforation or eye, or it may be fixed after proper adjustment has been obtained by means of a thumb screw 25 threaded through an opening in the head 19 and 80 bearing against the arm 22.

In applying the bracket to a bed-post, the thumb-screw 16 is backed sufficiently far to permit the frame 11 being placed against the post, after which the frame 12 is brought 90 against the opposite side of the post above the frame 11 and lowered thereon until the notches 14, 15, interengage, thereby uniting the two members of the bracket. The screw 16 is then tightened until the bracket has 95 been clamped firmly to a bed-post. The curved portion 24 of the arm 22 is then passed through the perforation 20 in the head 19 and the light adjusted as desired. The current for supplying light will pass by 100 means of wires through the arm 22. If the bracket is to be supported on a horizontal rail, as in Fig. 3, instead of a vertical post as in Fig. 1, the arm 22 of the fixture will pass through the perforation 21 in the head 19, the thumb-screw 25 serving to secure the arm 22 whether carried in the perforation 105 20 or 21.

When the fixture is to be supported by a post, shelf or other object made of wood, a 110

bracket such as shown in Fig. 5 may be employed. Here two sections 26, 27 having fingers 28, 29, respectively, are drawn together by a screw 30 to cause said fingers to grip the post or other object. From the finger 19 a head 31, similar to the head 19, is provided with right-angle perforations 20, 21, for the arm 22. This bracket may be raised and lowered on the vertical post, or moved longitudinally of its support if the latter is in a horizontal position, and has substantially all of the adjustments found in the preferred form.

What I claim as new is,—

- 15 1. An electric light fixture comprising a two-part bracket, said parts having hooked-shape terminal ends that co-operatively interlock around an article of furniture to which said bracket is adapted to be removably attached, a clamping screw threaded in one of said parts for fixing said bracket in place, and a head on the other part through which are formed two intersecting perforations at right angles to each other, and a
- 20 25 bent arm having an electric light on one end adapted to engage by its other end with either of said perforations and be moved freely therein for adjustment, the weight of the overhanging arm serving to maintain the same in its position of adjustment.
- 30 2. An electric light fixture comprising a bracket formed of two interengaging members having slotted ends that interlock with each other, a clamping screw threaded
- 35 30 through one of said members for supporting the bracket upon a piece of furniture, and a head projecting from the other member hav-

ing two perforations formed therein at right angles to each other.

3. An electric light fixture comprising a 40 bracket formed of two interengaging members, each of said members having a notch cut into one edge of each of its ends, the notches of one member being on the side opposite those of the other member and 45 adapted to interlock to hold said members together, means on one member for fastening the interlocking members of the bracket to an article of furniture, and means on the other member for adjustably attaching an 50 electric light thereto.

4. A bracket for supporting an electric light fixture to an article of furniture comprising two separable members, each of said members having a notch near each of its 55 ends extending in from one edge thereof, the notches in the respective members being on opposite sides to permit the ends of the members to engage and interlock about a portion of an article of furniture, a clamping screw threaded in one member for securing the bracket to an article of furniture, and a head with cruciform perforations projecting from the other member, either of said 60 perforations adapted to receive an electric 65 light fixture.

In testimony whereof I have hereunto set my hand in presence of two subscribing witnesses.

CLARENCE W. LUCAS.
